UNITED STATES PATENT OFFICE.

PHILIP W. SIEVERT, OF DAYTON, OHIO, ASSIGNOR TO METROPOLITAN MAUSOLEUM COMPANY, A CORPORATION OF NEW YORK.

MAUSOLEUM.

1,087,895.

Specification of Letters Patent. Patented Feb. 17, 1914.

Application filed July 11, 1913. Serial No. 778,490.

To all whom it may concern:

Be it known that I, PHILIP W. SIEVERT, a citizen of the United States, residing at Dayton, in the county of Montgomery and State of Ohio, have invented certain new and useful Improvements in Mausoleums; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to new and useful improvements in mausoleums.

The object of the invention is to provide a mausoleum of simple construction which is moisture proof, in which the bodies may 20 be interred in hermetically sealed crypts and which provides means for carrying off any gases that may arise from the bodies and escape from the crypts due to imperfections in sealing the crypts.

25 Referring to the accompanying drawings Figure 1 is a vertical lateral section through one series of crypts of the complete mausoleum the same being on the line *a—a* of Fig. 2; Fig. 2 is a horizontal section on the line 30 *b—b* of Fig. 1; and Fig. 3 is a front elevation of the crypts.

In the accompanying drawings, I have illustrated only one side of one wing of the mausoleum but it will be understood that all 35 sides of all wings are similarly constructed.

Referring more particularly to the drawings *H'* represents an outer foundation which supports the wall of the mausoleum. The said wall consists of an outer portion 40 *H* constructed of granite and an inner portion *I* constructed of concrete. Also supported on the foundation *H'* is an inner concrete wall *K* which, together with the outer wall, forms a vertical air passageway 45 *J* which communicates with the atmosphere at the bottom through ports *G* in the wall *H—I*. The ports *G* may be provided with any well known type of grid. The air passageway *J* communicates with the atmos-

50 phere at the top through ports *N* by way of a chamber *R*. The chamber *R* lies between the roof formed of an inner portion *Q* and an outer portion *P* and a slab *R'* one edge of which rests upon the inner wall *K*. The 55 mausoleum is provided with a floor *E'*

which forms the bottom of the lowermost crypts, and a floor *E''* for the corridor of the mausoleum. Beneath the floors *E'* and *E''* are chambers *S'* and *S''* which communicate through ports *S* in an inner foundation wall *H''*. The chamber *S'* communicates with the atmosphere through ports *G* and a port *F* in the inner wall *K*. The chambers *R*, *S'* and *S''*, the ports *N*, *G*, *F* and *S* and the air passageway *J* are instrumental in maintaining a circulation of air through the mausoleum, thereby preventing the accumulation of moisture.

Extending laterally from the inner wall *K* is a plurality of vertical division walls *K'* 60 which are connected by a plurality of horizontal shelves *L'*. The walls *K'* and the shelves *L'* form a plurality of crypts in which the bodies are deposited. The rear ends of the crypts are formed by the inner wall *K* while the front ends are adapted to be closed by inner slabs *D* and outer slabs *B*. At the time the bodies are placed within the crypts they are accompanied by suitable chemicals which are instrumental in their 65 desiccation. To permit the excessive accumulation of moisture within the crypts to be drained therefrom, the rear wall *K* is provided, at the lower rear portion of each crypt, with drain ports *M* which communicate with vertical tubes *L*, mounted in the wall *K*. The tubes *L* extend downwardly and enter a chamber *T* containing disinfecting chemicals *U* and a drain pipe *V*. The slabs *B* and *D* form an air passageway *C* at 70 the front of the crypts. The passageway *C* extends through openings *X* in the shelves *L'*, and communicates with the chamber *S* at the bottom through a port *E* and the atmosphere at the top through a ventilator 75 *O*, thereby providing for a circulation of air in the passageway *C*. The passageway *C* is also instrumental in carrying off any vapors that may escape from the crypts past the slab *D* due to imperfections in the setting 80 of said slabs. The front of the crypts are also provided with ornamental slabs *A* which are preferably of marble and which lie against the outer slabs *B*.

I claim.

1. In a structure of the character specified, vertical rear and side walls, in combination with a plurality of shelves coöperating therewith to provide a plurality of crypts, the entrance to each of said crypts being 110

closed by outer and inner series of slabs which provide between them air spaces at the front of the structure, the forward ends of the shelves being extended across said air spaces to support said slabs and provided with openings to permit said air spaces to form a continuous air passage throughout the depth of the structure, substantially as specified.

10 2. In a structure of the character specified, the combination of inner and outer rear walls and side walls forming an inclosure, a plurality of shelves dividing said inclosure into a series of crypts, the rear walls providing an air-circulating passage extending

the height of the structure, two series of slabs closing the front of said crypts and forming a vertical tier of air spaces thereat, the forward ends of said slabs being extended across said air spaces to support said slabs and having openings providing communications between the vertical tier of air spaces at the front of the structure, substantially as specified.

15 In testimony whereof I affix my signature, in presence of two witnesses.

PHILIP W. SIEVERT.

Witnesses:

R. J. McCARTY,
MATTHEW SIEBLER.
